WINDOW SCREEN

Herman O. Kraft, Detroit, Mich.

Application October 23, 1941, Serial No. 416,145

8 Claims. (Cl. 160—94)

This invention relates to window screens, and more particularly to a novel screen for and in combination with a fenestral sash or other pivoted outwardly swingable window.

In sashes of this type swingably disposed within a suitable frame it is desirable that the screen member therefore be maintained on the inside thereof to permit free outward movement of the sash.

Heretofore various closure operators or levers have been employed for opening and closing fenestral sashes or maintaining the same in any particular angular position with respect to the window frame.

Various types of closable openings have heretofore been employed within the screen for receiving said closure operators to permit manual regulation thereof.

This opening in the lower portion of the screen member also serves the further purpose of receiving a window latch or locking means and permitting entry of the hand for operating said latch which is secured to the lower portion of said sash for locking and unlocking the same with respect to a sill or stationary window frame when the swinging transom is located above the lower stationary window panels.

In each and every one of said devices it appears that some method or device was used for closing said opening when the window was opened in order to prevent the entry of insects, etc.

However, such openings when employed in factories and tool shops have been convenient for unfaithful employees in throwing out tools and other small equipment to be later picked up from the outside. Thousands of dollars are spent each year by manufacturers in replacing tools, etc., which are so disposed of.

In order to prevent these losses, the present invention embodies a novel lower screen element with the opening in the screen omitted and in its place substituting a pressed or otherwise suitably formed inwardly concaved recess for receiving the window latch as described hereinafter.

Consequently it is the purpose of this invention to provide the combination with the outwardly swingable fenestral window a suitable screen for receiving the window latch and the closure operator, and at the same time eliminating the opening heretofore provided for that purpose.

It is the further purpose hereof to provide a screen member through which the closure operator is slidably and through which the fingers

of an individual may be inserted for actuating the window locking latch.

The invention relates to the various elements and combinations thereof hereinafter set out in detail in connection with the appended drawing of which:

Figure 1 is a sectional side elevational view of the screen and fenestral window.

Figure 2 is a front elevational view thereof from the inside.

It is to be understood that the particular arrangement of elements illustrated and described herein is merely the preferable embodiment of the invention by way of example, as it is not the purpose of the inventor to limit the invention thereby.

In the drawing the frame 11 has horizontally pivoted at 12 therein the fenestral sash 13 with the glass members 14. The lower section of said

20 sash is adapted to swing outwardly upon said pivots with its upper portion swinging inwardly; and is adapted for adjustment in a plurality of angular positions with respect to said frame.

The screening for said window consists of an upper screen or other suitable wire mesh 15 fixedly retained and supported by the moulding or bars 16 within frame 11 on the outside of sash 13.

The lower section of screen or wire mesh 17 supported within moulding 18 is disposed vertically within frame 11 upon the inside of the sash 13, whereby the latter is free to swing outwardly with respect to a sill member 19. In applicant's preferable embodiment the lower 35 screen section 17 is provided with a centrally disposed inwardly concaved recess 20 formed therein. It will be noted that said recess may be formed in any one of a plurality of ways such as, by pressing, or assembling.

40 The lower portion of the sash 13 has pivotally secured thereto a closure operator arm 21 provided with a plurality of notches 22 in the lower surface thereof for selective cooperating engagement with the sill member 19 for maintaining sash 13 in any desired angular position with respect to frame 11.

45 It will be noted that the closure operator 21 is adapted for entry through screen member 17 thereby permitting angular adjustment of said window.

50 A latch member 23 is also pivoted to the lower portion of sash 13 adjacent the pivotable connection of the closure operator arm for locking and unlocking said sash 13 with respect to sill 19.

55 The concave recess 20 within screen member

17 is adapted to receive said latch whereby the same may be manually or mechanically opened or closed by the insertion of one's fingers or bars through the wire mesh adjacent said recess 20.

By the provision of said recess 20 it is seen that no opening is necessary within screen member 17; and by eliminating said opening it is impossible for an employee to throw out tools or equipment to be later picked up.

Consequently, it will be seen that by the provision of said recess which may be disposed in any convenient position the objects heretofore set out are accomplished.

It is also included as within the scope of this invention that such a pivotal window sash may be operated in the combination without the use of the arm or lever 21, though the same is desirable.

Furthermore it will be seen that the invention includes a window sash which merely swings outwardly from either its top or bottom. That is, the combination is equally applicable even though no portion of the sash is swingable inwardly.

It will be further noted that the invention is equally adaptable to a vertically hinged or pivoted window with the recessed screen member on the inside thereof.

Having described the invention in detail, reference should now be had to the claims which follow for determining the scope of my invention:

I claim:

1. In a screen for a window sash pivotally mounted in a frame, a screen one portion of which is mounted inside the face of said frame adjacent the upper half of said window on the outside thereof, and the other portion is secured inside the face of said frame adjacent the lower half of said window on the inside thereof, said lower portion being provided with an inwardly bulged portion forming a recess, a window actuating lever joined to said sash, adapted for entry through said screen, and a latch pivoted to said sash adapted to be nested within said recess in closed position of said sash.

2. In a screen for a horizontally pivotal sash mounted in a frame, a wire mesh inside the face of said frame adjacent the upper half of said sash on the outside thereof, a wire mesh inside the face of said frame adjacent the lower half of said sash on the inside thereof, being provided with an inwardly bulged portion forming a recess, an actuating lever joining said sash adapted for entry through said mesh, and a latch secured to said sash adapted to be nested within said recess in closed position of said sash. 55

3. In a screen for a horizontally pivotal sash mounted in a frame, a screen adjacent the upper half of said sash on the outside thereof, a screen adjacent the lower half of said sash on the inside thereof provided with an inwardly bulged recessed portion, and a latch means secured to said sash adapted to be nested within said recess when the sash is in closed position.

4. In a screen for a pivoted window sash mounted in a frame, a wire mesh adjacent said frame on the inside of said sash, provided with an inwardly bulged recessed portion, a sash opening and closing means, and a latch means connected to said sash adapted to be nested within said recess when in closed position, access to said latch being through the mesh surrounding said recess.

5. The combination with a screen for a hinged window sash mounted in a frame having a sill, 20 a wire mesh member adjacent said frame on the inside of said sash provided with an inwardly bulged recessed portion, a sash actuating means, and a latch connected to said sash adapted to be nested within said recess when in locking engagement with said sill, said latch being manually or mechanically accessible through the mesh surrounding said recess.

6. In a screen for a pivoted window sash mounted in a frame, a wire mesh member adjacent said frame on the inside of said sash, provided with an inwardly bulged recessed portion, a sash opening and closing means joined to said sash and adapted to adjustably extend through said mesh for manual or mechanical application, and a latch connected to said sash adapted to be nested within said recess when in closed position of said sash, manual or mechanical access to said latch being through the mesh surrounding said recess.

7. In a covering for a sash, a mesh member on the inside thereof having an inwardly bulged recessed portion, and a latch connected to said sash adapted to be nested within said recess when said sash is in closed position, access to said 45 latch being through the mesh surrounding said recess.

8. In a screen for a pivoted window sash mounted in a frame, a wire mesh adjacent said frame on the inside of said sash, provided with an inwardly bulged recessed portion, and a latch means connected to said sash adapted to be nested within said recess when in closed position, said latch being accessible through the mesh surrounding said recess.

HERMAN O. KRAFT.
